UNITED STATES PATENT OFFICE.

LACEY Y. WILLIAMS, OF TOLEDO, OHIO.

DESIGN FOR A TOY CANNON.

50,370.

Specification for Design.

Patented Feb. 20, 1917.

Application filed May 17, 1916. Serial No. 98,230. Term of patent 7 years.

To all whom it may concern:

Be it known that I, LACEY Y. WILLIAMS, a citizen of the United States, residing at Toledo, in the county of Lucas and State of Ohio, have invented a new, original, and ornamental Design for a Toy Cannon, of which the following is a specification, reference being had to the accompanying drawing, forming part thereof.

The figure is a perspective view of a toy cannon, showing my new design.

I claim:

The ornamental design for a toy cannon, substantially as shown.

LACEY Y. WILLIAMS.
